(57) **CLAIM**

The ornamental design for a packaging container, as shown and described.

DESCRIPTION

FIG. 1 is a perspective view of a packaging container showing our new design which consists of a lid member and a body member;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front elevational view of the lid member of the packaging container of FIG. 1;

FIG. 9 is a rear elevational view of FIG. 8;

FIG. 10 is a top plan view of FIG. 8;

FIG. 11 is a bottom plan view of FIG. 8;

FIG. 12 is a right side elevated view of FIG. 8;

FIG. 13 is a left side elevational view of FIG. 8;

FIG. 14 is a front elevational view of the body member of the packaging container of FIG. 1;

FIG. 15 is a rear elevational view of FIG. 14;

FIG. 16 is a top plan view of FIG. 14;

FIG. 17 is a bottom plan view of FIG. 14;

FIG. 18 is a right side elevational view of FIG. 14;

FIG. 19 is a left side elevational view of FIG. 14; and,

FIG. 20 is a sectional view taken along the line 20—20 of FIG. 4 with the lid member in a closed position.

The broken lines showing a plate spring in FIGS. 16 and 20 are for illustrative purposes only and form no part of the claimed design.
